DESIGN FOR A BLOUSE

William Freedman, New York, N. Y.

Application March 13, 1935, Serial No. 55,861

Term of patent 3½ years

To all whom it may concern:

Be it known that I, William Freedman, a citizen of the United States of America, residing in Manhattan, county of New York, and State of New York, have invented a new, original, and ornamental Design for a Blouse, of which the following is a specification, reference being had to the accompanying drawing, forming part thereof, wherein,

The stitchings on the collar and front panel of the blouse represent quilting.

I claim:

The ornamental design for a blouse, substantially as shown and described.

WILLIAM FREEDMAN.
